VAPOR ELECTRIC CONVERTER

Ernest G. Bangratz, Wilkinsburg, Pa., assignor to
Westinghouse Electric & Manufacturing Com-
pany, East Pittsburgh, Pa., a corporation of
Pennsylvania

Application December 28, 1933, Serial No. 704,307

5 Claims. (Cl. 250—27.5)

My invention relates to a vapor electric converter and particularly to a make-alive mounting for such converters.

In the construction of vapor electric converters of the make-alive type, considerable difficulty has been experienced in properly mounting the make-alive electrode so that it will remain in contact with the cathode of the converter.

It is an object of my invention to provide an improved make-alive mounting for such converter.

It is a further object of my invention to provide an improved cathode construction to reduce the amount of cathode material required in such converters.

In the converter, according to my invention, the cathode lead and the make-alive electrode with its accompanying leads are mounted as part of a press and the press assembled to form 20 part of the rectifier envelope. In order to secure the desired positioning of the make-alive electrode, the press is first constructed with electrode leads sealed in place and then the electrode proper mounted in proper position on the 25 lead in conductor and secured firmly in place before the press is sealed to the main body of the converter.

Other objects and advantages of my invention will be apparent from the following detailed 30 description taken in conjunction with the accompanying drawing, in which

The single figure is an elevational view, partly in section, of a converter embodying my invention.

35 The apparatus, according to my invention comprises an evacuated container 1 of glass or other suitable material having an anode 2 sealed therein, a cathode 3 of vaporizable material and a suitable make-alive electrode 4. The 40 cathode lead 5 and the supply lead 6 for the make-alive electrode 4 are assembled in a substantially tubular vitreous seal 8 known in the art as a press.

The cathode lead 5 is preferably sealed into 45 the press 8 and in order to reduce the quantity of mercury required for the cathode 3, the cathode lead 5 is distorted so as to extend downward in substantially parallel relation to the body of the press 8. This cathode lead 5 is extended 50 almost to the bottom of the press.

In order to prevent the cathode spot from attaching to that portion of the cathode lead 5 extending above the mercury surface, it is desirable to provide an insulating coating 10 of 55 suitable material such as glass extending from

the press to a point below the surface of the cathode material 3. It has been found that if this insulating surface 10 does not extend an appreciable distance below the cathode surface, the cathode spot may attach itself to the cathode lead and strip the insulating covering 10 from this lead 5.

The make-alive lead 6 preferably extends upwardly substantially centrally of the converter chamber 1 and is provided with threads 12 for 10 the attachment of the make-alive electrode 4.

This attachment preferably comprises a laterally extending arm 14 having a threaded opening 15 for engagement with the threads 12 on the make-alive lead 6. At the end of this arm 15 14 remote from the sealed in make-alive lead 6, is a second threaded opening 16 for engagement with a threaded electrode stem 17. This stem has attached thereto the make-alive electrode 4 preferably of resistance material such as carbo- 20 rundum or boron carbide.

In constructing my device, the leads 5 and 6 are first sealed into the press 8 in a well-known manner and the arm 14 is engaged in threaded relation with the make-alive lead 6 and the make- 25 alive electrode stem 17 threaded into engagement with the laterally extending arm 14.

Obviously, the position of the electrode 4 may be adjusted by means of the threaded connections both between the electrode stem 17 and 30 between the threaded lead 6 in the transverse arm. After the electrode 4 has been assembled in the desired position, it is desirable to deform a portion of the arm 14 adjacent to the threaded connections 15, 16 in order to prevent relative 35 motion between the component parts. This is most easily done by clamping the arm 14 in a vise and applying pressure laterally of the threaded openings 15, 16.

It has sometimes been found desirable to provide a shield member between the anode 2 and the cathode 3 of such converters. Such shields can easily be mounted according to my invention by extending the make-alive lead 6 upward beyond the laterally extending arm 14 and providing the shield 20 preferably of disk shape and attaching the same by suitable nuts 21. If desired, these nuts 21 may be deformed by lateral pressure to prevent displacement during the operation of the device.

If desired, the envelope 1 may be provided with a suitable metallic base to secure ease of mounting or connecting the device in operation circuits. For this purpose, I have shown a substantial cylindrical shell 25 in engagement with the bot- 55

tom portion of the evacuated envelope 1 and having an insulated closure 26 supporting contact fingers 28 to which the make-alive lead 6 and the cathode lead 5 are connected in any suitable manner.

5 While I have shown and described a particular embodiment of my invention, it will be apparent that changes and modifications can be made therein without departing from the true spirit of 10 my invention or the scope of the appended claims.

I claim as my invention:

1. A vapor-electric converter, comprising an evacuated container, a mercury pool in said container, a plurality of leads sealed into said container and extending above said mercury pool, one of said leads being bent into contact with said pool and having a portion immersed therein, an insulating covering on said lead between the seal and the pool, said covering extending below 20 the mercury surface, a laterally extending arm on another of said leads, a make-alive electrode depending from said arm and having the tip thereof in contact with the mercury and a shield member attached to and supported by said lead 25 above the laterally extending arm.

2. In a vapor-electric converter, a mercury cathode, a lead extending through said cathode and insulated therefrom, an arm attached to said lead and extending beyond the insulator for 30 said lead, an electrode stem secured to said arm and an electrode of resistance material secured to said stem, said electrode having the tip thereof in permanent contact with said mercury cathode.

3. A vapor-electric converter comprising an anode, a vaporizable cathode cooperating therewith, an auxiliary electrode in intimate contact with said cathode and a combined support and lead-in conductor for said auxiliary electrode comprising a stem secured to said electrode, a lead-in 5 extending into said converter and a threaded connection between said lead-in and said stem.

4. An electrode assembly for a vapor-electric device comprising a stem extending upward 10 through the cathode, an insulating covering separating said stem from the cathode and providing a vacuum-tight seal for said stem, threads on that portion of the stem extending above the insulating covering, a laterally extending arm 15 having a portion in threaded engagement with said stem and a make-alive electrode secured to said arm and extending into permanent contact with said cathode.

5. An electrode assembly for a vapor-electric 20 device comprising a stem extending upward through the cathode, an insulating covering separating said stem from the cathode and providing a vacuum-tight seal for said stem, threads on that portion of the stem extending above the 25 insulating covering, a laterally extending arm having a portion in threaded engagement with said stem, and a make-alive electrode secured to said arm and extending into permanent contact 30 with said cathode, and a shield secured to said stem above said arm.

ERNEST G. BANGRATZ.
